CLAIM

The ornamental design for a substrate with camouflage pattern, as shown and described.

DESCRIPTION

The file of this patent contains at least one drawing/photograph executed in color. Copies of this patent with color drawing(s)/photograph(s) will be provided by the Patent and Trademark Office upon request and payment of the necessary fee.

FIG. 1 is a perspective view of a substrate with camouflage pattern showing our design; and,

FIG. 2 is a perspective view of an alternative embodiment of a substrate with camouflage pattern shown in color.

**1 Claim, 2 Drawing Sheets
(1 of 2 Drawing Sheet(s) Filed in Color)**

FIG. 1

FIG. 2
